UNITED STATES PATENT OFFICE

BALTHASAR VAN DER POL, OF EINDHOVEN, NETHERLANDS, ASSIGNOR TO THE RADIO CORPORATION OF AMERICA, A CORPORATION OF NEW YORK

MULTIVIBRATOR

Application filed January 11, 1927, Serial No. 160,507, and in the Netherlands January 12, 1926.

The present invention has reference to a so-called multi-vibrator circuit-arrangement. In its original form such arrangement consists essentially of an even number of triodes 5 mutually coupled in resistance amplifying circuits, the anode of the last triode being coupled retroactively to the grid of the first one. Such system in its simplest arrangement (comprising but two triodes) is diagrammatically shown in Figure 1 of the accompanying drawing. Intense current impulses periodically occur in these systems, the frequency of said impulses being determined by the values of C and R. 10 According to the invention the same results are reached with half the number of thermionic apparatus, provided the triodes are replaced by tetrodes (double-grid valves), between the two grids of which the periodically discharged condenser is interposed, one 20 of said two grids being connected to the cathode across the leak resistance. 25 An electrical-scheme of an embodiment of the invention is shown in Figure 2. In a discharge tube are sealed an anode A, a filament F and between them two grids G₁ and G₂. The filament F is supplied from a battery B₁ and the current in the anode circuit is supplied by a battery B₂, and if 30 desired, by a battery B₃ connected in series therewith. The point P of the anode circuit is connected directly to the grid G₁ and with the interposition of a condenser C (which may be adjustable or not) to the other grid G₂. The latter grid is finally connected 35 through a leak resistance R to the filament. The value of the condenser C should be, for example, between 2000 centimeters and 1 microfarad, the resistance r being at this point 40 some thousands of ohms and the resistance R being about 1 megohm.

In such a system periodic current impulses are maintained, which are audible, for example, in a telephone or other receiving apparatus T in the anode circuit. This phe-

nomenon may briefly be explained somewhat as follows: During each impulse the condenser C is discharged and in the reverse sense recharged at a very high starting speed which, however, gradually decreases until again a discharge occurs but by this time in the reverse sense. The low selfinduction present in the connecting wires maintains the phenomenon in somewhat the same manner as that in which too small a flywheel maintains the operation of a piston-machine having two dead points. The smaller the said selfinduction, the more different from the sine-shape will be the current curve of the discharges and the more easily it will be possible, if so desired, to sift out very high harmonics. Thus, it is, for example, possible to generate radiofrequencies in a high frequency circuit coupled across a high frequency transformer to the anode circuit, the oscillations generated in the anode circuit being comprised within the audible region.

What I claim is:

1. A multivibrator comprising a multi-electrode space discharge device including two grids, a cathode, and a plate electrode, a condenser coupling the grids, a leak resistance connecting one of said grids to the cathode, and the other grid being connected to the cathode through a source of high potential, and a connection between the plate and said source of high potential.

2. A multivibrator comprising a tetrode having two grids, a cathode, and a plate electrode, a condenser coupling the grids, a leak resistance connecting one of said grids to the cathode, a source of high potential connected to the plate, and a resistance connecting the other of said grids to the source of high potential.

3. A multivibrator comprising a tetrode having two grids, a cathode, and a plate electrode, a condenser coupling the grids, a leak resistance connecting the grid located adjacent to the plate, to the cathode, and a source

of high potential connected to the other of
said grids and the plate.

4. A multivibrator comprising a multi-electrode space discharge device including
5 two grids, a cathode, and a plate electrode,
a condenser coupling the grids, a leak re-sistance connecting one of said grids to the
cathode, and the other grid having a poten-tial approaching that of the plate, and a
10 source of potential connected to the plate.

10 In testimony whereof I affix my signature,
at the city of Eindhoven, this 13th day of
December, 1926.
